TO RADIO CORPORATION OF AMERICA, OF NEW YORK, N. Y., A CORPORATION OF
DELAWARE

VOLUME CONTROL

Application filed July 24, 1929. Serial No. 380,713.

This invention relates to a volume control for audion amplifiers and particularly to a volume control for cascaded amplifiers.

Because of the highly specialized conditions under which radio receivers are operated on aircraft, the invention is particularly useful in connection with such receivers but it will be apparent that the novel method of control may be applied to any cascaded amplifier.

The relatively small collector systems employed on aircraft necessitate the use of a plurality of stages of radio frequency amplification, and the rapidly varying field strength encountered when the aircraft is in the neighborhood of the radio beacon or transmitter station calls for an extended range of amplification or volume control.

It has been proposed to control the amplification by regulating the filament or cathode heater current supplied to a plurality of the cascaded stages, the several filaments or cathode heaters being in parallel with each other, and in series with the source of supply and a common resistance. An amplification control of this type does vary the amplification or output volume over an extended range, but it is open to the serious objection that it is commercially impracticable to construct an adjustable resistance which, throughout the range of adjustment of the resistance, will produce equal or approximately equal changes in amplification for a given angular adjustment of the control device. In some ranges of adjustment of the control device, the change in amplification was relatively small or substantially negligible, while in another range the amplification changed at such a rapid rate that considerable difficulty was experienced in setting the control device to effect the desired amplification.

An object of the present invention is to provide a cascaded amplifier including an adjustable resistance common to the filament or cathode heater circuits of a plurality of stages, and in which the change in amplification, for a given change in the setting of the contact arm of the resistance, may be substantially constant throughout the range of adjustment of the resistance. A

further object is to provide, in a cascaded amplifier having its filaments fed in parallel from a common source and through a single adjustable resistance, resistances individual to the filament circuits of the several audions for placing the operating points of the respective audions upon different portions of their gain-filament voltage characteristic. More specifically, an object is to provide a cascaded amplifier in which a resistance is included in the filament circuit of one tube for shifting its operating point to a portion of the gain-filament voltage characteristic at which the slope is substantially different from that which another audion of the amplifier is operating.

These and other objects of the invention will be apparent from the following description, when taken with the accompanying drawings in which,

Fig. 1 is a circuit diagram of a radio receiver embodying the invention,

Fig. 2 is an experimental curve indicating the relationship between stage gain and volume control voltage in a single stage, and

Fig. 3 comprises curves plotted from experimental data taken with a receiver including a two stage radio frequency amplifier embodying the invention, and the receiver when the two stage amplifier was provided with a volume control of the previously known type.

The circuit diagram of Fig. 1 illustrates a receiver having two tuned radio frequency stages with tetrodes T', an audion detector D and two audio amplifying audions A. Except for the circuit elements, shown by the heavier lines, which supply current to the filaments of the radio frequency amplifiers T₁, the electrical and mechanical arrangement of the receiver forms no part of the present invention.

The filaments of the amplifiers T' are fed, in parallel, from a source of current such as battery A, and the portion of the supply circuit common to both filaments includes the volume control resistance R, a fixed control grid bias resistance R_c, and preferably a fixed resistance R₂ which limits the maximum

voltage that may be impressed across the filament circuits.

The circuit arrangement, so far as described, is of conventional form. In accordance with the present invention, a resistance

5 R_3 is provided in the filament circuit of only one of the amplifiers to reduce the filament voltage on that tube below that applied to the other tube.

10 The effect of the added resistance R_3 will be apparent from a consideration of the characteristic curve shown as Fig. 2. The curve was plotted from data obtained experimentally with a tetrode of the type known commercially as UX 222 and represents, for 15 a single radio frequency stage, the variation of amplification with filament voltage. The normal or maximum filament voltage for tetrodes of this particular type is 3.3 volts, 20 and it is to be noted that this voltage places the operating point of the tube at a point A, i. e., past the knee of the curve.

To decrease the amplification of a single stage, or a plurality of stages operated under 25 identical conditions, the voltage control resistance must be turned through a substantial arc away from its maximum voltage (knee of the curve) adjustment before appreciable volume control is effected.

30 By initially shifting the operating point of one tube to a lower section of the characteristic, for example to point B, the amplification of the cascaded stages will be changed at different rates as the filament 35 voltages on all stages are simultaneously reduced. Starting with normal or maximum overall amplification, as the resistance is adjusted to decrease the filament voltages, the gain of the tube operating at point B decreases at a comparatively rapid rate while the decrease for the tube operating at point A is negligible. As the resistance is adjusted to vary the amplification of the first 40 tube along the upright portion of the characteristic, the change in amplification of the second tube is appreciable but is of a decidedly lower order of magnitude. When the 45 operating point of the second tube is upon the upright portion of the characteristic, the first tube is operating in the region of lower slope. By an appropriate choice of the spacing of the operating points, the variation in overall amplification, for a given angular 50 adjustment of the resistance, may be made approximately uniform throughout the range of adjustment of the control device.

55 Reverting now to Fig. 1, it will be apparent that the effect of the added resistance R_3 is to shift the normal operating point of the first amplifier to a region of the characteristic at which the slope is much steeper than at the normal operating point of the second tetrode.

The curves forming Fig. 3 represent the 60 observed performance of the amplifier of

Fig. 1 for different values of the added resistance R_3 . The ordinates represent sensitivity on a logarithmic scale and the abscissa indicate angular adjustment of the dial of the volume control resistance.

70 By sensitivity is meant the signal strength or input to the receiver required for a predetermined constant output since the effect upon the ear of a given signal varies as the logarithm of input energy, the curves indicate the relationship which must be maintained between control dial setting and signal strength if, for varying signal strength, the output volume is to be maintained constant.

75 Curve C was plotted from data obtained when the resistance R_3 was omitted, and R_2 and R_c were 3.6 and 6 ohms respectively. With these values for the fixed resistances, a 6 volt battery A, and a volume control resistance adjustable from zero to 20 ohms, 80 the control dial setting of "80" placed the normal operating potential, 3.3 volts, on the filaments of both tubes. It will be noted that practically all of the volume control falls within less than one-third of the effective 85 operating range of the control dial.

90 The data of curve D was obtained when a 6 ohm resistance was introduced into the filament circuit of the first tetrode, as indicated by R_3 in Fig. 1. This initial shifting of the 95 operating point of the first tetrode results in a slight decrease in the sensitivity of the amplifier, i. e., a slight reduction in the maximum overall amplification, and distributes the control substantially uniformly over the 100 range of adjustment of the control device.

105 As indicated by curve E, the normal operating point of one tube may be shifted to a still lower point on the curve. In this instance, a 10 ohm resistor was inserted as R_3 , but this further displacement of the normal operating point of one tube substantially 110 decreases the maximum overall amplification and reduces the effective range of adjustment of the control dial.

115 While I have described the invention as applied to a two stage amplifier, it is to be understood that the invention is not limited to a volume control based upon any particular number of cascaded stages, or to the particular values of resistances specified above.

120 The value of the resistance R_3 depends, of course upon the type of tube and the number of stages subjected to volume control. When more than two stages are used, the normal operating points of the several stages are displaced to fall upon different portions of the gain-control voltage characteristic by inserting, in all but one stage, resistances R_3 of different values.

125 The invention is equally applicable to triode tubes and to tubes employing separate heaters for the cathode.

I claim:

1. In a cascaded amplifier, a plurality of 130

audions having substantially identical characteristics, a source of current, circuit elements connecting the filaments of the several audions in parallel with each other and across said current source, an adjustable resistance included in the filament circuits of all of said audions, and a voltage-reducing resistance in the filament circuit individual to one of said audions.

10 2. The invention as set forth in claim 1, wherein the magnitudes of the resistances are so related that for all adjustments of said adjustable resistances, the operating points of said audions fall upon portions of the characteristic curve which are of substantially different slope.

3. A cascaded audion amplifier of the type including a volume-control resistance for simultaneously adjusting the filament voltages impressed upon a plurality of substantially identical audions included in the respective stages, characterized by the fact that the filament circuit of one stage includes a resistance which decreases the voltage across 25 the filament of that tube below the value of the filament voltage across the tube included in another stage of said amplifier.

4. In an amplifier, a plurality of cascaded amplifier stages including audions of substantially identical characteristics, a source of current for energizing the filaments of all stages, an adjustable resistance in series between said source and said filament circuits, and a resistor in the filament circuit of one 35 stage effective to decrease the filament voltage of that stage to shift the operating point thereof to a portion of the characteristic curve having a slope differing substantially from that at the operating point of another stage.

40 5. In a cascaded amplifier, a plurality of audions, a source of current for heating the cathodes of said audions, an adjustable resistance common to the cathode heating circuits of all of said audions, and a resistance in the heating circuit of one audion and of such magnitude that the operating temperature of the cathode of that audion is reduced below the point corresponding to maximum amplification when the said adjustable resistance 45 has such effective value that the cathode of another audion has a temperature effective to give maximum amplification.

55 6. In the operation of a cascaded audion amplifier, the method of effecting amplification control by simultaneous adjustment of the temperatures of the cathodes of the audions included in said stages, which comprises initially adjusting the amplifier for maximum amplification by decreasing the 60 temperature of one audion cathode to a point corresponding to less than maximum amplification of that audion while operating the cathode of another audion at a temperature giving rise to approximately maximum amplification, and simultaneously reducing the

temperatures of both cathodes to lower the amplification of said amplifier.

7. In a cascaded radio frequency amplifier, a plurality of electron discharge tubes, a source of current for energizing the cathodes of said tubes to emit electrons, an adjustable resistance common to the cathode energizing circuits of all of said tubes, and an impedance in the energizing circuit of the first of said tubes and of such magnitude that the operating electron emissivity of the cathode of that tube is reduced below the point corresponding to maximum amplification when the said adjustable resistance has such effective value that the cathode of a following tube 75 has an emissivity effective to give maximum amplification.

8. In the operation of a cascaded radio frequency amplifier, the method of effecting amplification control by simultaneous adjustment of the electronic emissivity of the cathodes of the tubes included in the amplifier, which comprises initially adjusting the amplifier for maximum amplification by decreasing the electron emission of the cathode 85 of at least one of the tubes to a point corresponding to less than maximum amplification of that tube while operating the cathode of at least another tube with electron emission giving rise to approximately maximum amplification, and simultaneously reducing the electron emission of both cathodes to lower the 90 amplification of said amplifier.

In testimony whereof, I affix my signature.
